(Cl. D48—20)

To all whom it may concern:

Be it known that we, Robert D. Pfister and Arthur O. Pfister, citizens of the United States of America, residing at Rocky River and Cleveland Heights, respectively, county of Cuyahoga, and State of Ohio, have invented a new, original, and ornamental Design for Combined Lamp and Shade, of which the following is a specification, reference being had to the accompanying drawing, forming a part thereof, in which:

Fig. 2 is a perspective view of the lamp with the shade removed; and

Fig. 3 is a top plan view of the lamp and shade.

The dotted lines shown in the drawing are for illustrative purposes only.

We claim:

The ornamental design for a combined lamp and shade, substantially as shown and described.

ROBERT D. PFISTER.

ARTHUR O. PFISTER.
